UNITED STATES PATENT OFFICE

ANDREW J. McEWAN, OF TULSA, OKLAHOMA

AUTOMATIC STOP COCK

Application filed September 30, 1926. Serial No. 138,781.

This invention relates to automatic stop cocks for fluid pressure flow lines, such, for example, as those of oil and gas wells.

In order to maintain an oil and gas well 5 in proper flowing condition for the raising of the oil to the surface, it is desirable to check or stop the flow of gas at intervals in order to build up the pressure of the gas and utilize its force for an oil raising action. 10 This has usually been accomplished heretofore by the use of a hand cock in a pipe line leading from the well, which practice is open to many objections. In some instances automatic stop cocks have been used for the purpose, these usually consisting of modified weighted-lever fluid pressure regulating valves, but these have been found inefficient, because of the inability to secure a proper and reliable valve closing action succeeding 15 each pressure releasing action.

The main object of my invention is to provide an automatic pressure controlled stop cock or valve which may be set to allow the gas pressure to build up to a desired degree, 20 and which will then release the pressure and permit it to fall to any predetermined degree, and which will then establish a positive cut off action to allow the pressure to again build up for a succeeding oil raising and pressure 25 reducing action.

Another object of the invention is to provide a valve having a desirable retarding action to prevent closing of the valve after it has been opened until the pressure has been 30 reduced to the proper point, and which will then positively close for the succeeding pressure building up action.

Still another object of the invention is to provide an automatic stop valve or cock which 35 is simple of construction, reliable and efficient in action, and adapted to be made, installed and kept in working order at a comparatively low cost.

The invention consists of the features of 40 construction, combination and arrangement of parts, hereinafter fully described and claimed, reference being had to the accompanying drawings, in which:—

Figure 1 is a diagrammatic section through 45 the stop cock or valve, showing the valve as

applied for use. For the purpose of making the operation clear, the valve casing is shown in section at right angles to its normal position, i. e., to its plane of section shown in Figure 2.

Figure 2 is a vertical longitudinal section through the stop cock or valve, showing the valve casing in its proper relation in such a view to the remainder of the device.

In carrying my invention into practice, I provide an automatic stop cock or valve comprising a valve casing 1 and a lever casing 2, the latter extending longitudinally from the valve casing and communicating at its inner end with the latter through a port or passage 3. The valve casing is provided with an outer chamber 4 and an inner chamber 5, said inner chamber being formed by a partition wall 6. In one side of the partition 6 is formed a passage 7 communicating with an inlet port 8, and in the diametrically opposite side of the casing is formed an outlet or discharge passage 9 communicating with the chamber 4. Openings 10 and 11 are provided at the top and bottom of the inner chamber 5 in which are fitted valve seats 12 and 13. A double valve comprising valve members 14 and 15 is provided to control the openings 10 and 11, the valves 14—15 being adapted respectively to govern such openings and engage such seats 12 and 13. The valves are balanced with relation to each other and when seated close communication between the inner chamber and outer chamber, the inner chamber being, however, always in communication with the inlet 8 through the passage 7. When the valve members are raised to open position, communication is established between both the ports 8 and 9, and both chambers 4 and 5 and the chamber 2, the last-named chamber being always in communication through the opening 3 with the chamber 4.

The valve members 14 and 15 are carried by a vertically movable stem 16 which extends upwardly through the opening 3 into the inner end of the casing 2 and through an opening in a closure plate 17 engaging a threaded opening 18 in the top of the casing, such opening 18 being provided to permit

ready and convenient initial assemblage of the parts of the valve structure and allow access thereto for repairs or other purposes. Secured to this plate 17 is a bonnet 19 having 5 a threaded opening 20 at its upper end receiving an adjustable stem 21 adapted to be secured in adjusted position by a securing nut 22 and carrying at its lower end an abutment head or flange 23. Secured to the upper end 10 of the valve stem 16 is a guide cage or cylinder 24 receiving and moving in guided connection with the head or flange 23 of stem 21 and enclosing a pressure spring 25 disposed between the abutment flange and bottom of 15 the cage and adapted to exert a downward pressure on the valve stem for a valve closing operation. By adjustment of the abutment stem 21 the tension or working pressure of this spring 25 may be regulated, as will be 20 readily understood.

Arranged in the casing 2 and extending longitudinally thereof is a valve controlling lever 26 which is pivotally coupled at its inner end to the valve stem, as indicated at 25 27. This lever passes, intermediately of its length, through an opening in the roller bearing 28 which is journaled in a fulcrum block 29, the roller 28 and block 29 forming a shifting fulcrum for the lever 26 whereby 30 the effective lengths and power ratios of its arms extending on opposite sides of the fulcrum may be varied. A rod 30 is secured at one end to the fulcrum block and extends at its opposite end outwardly through a stuffing-box 31 at the outer end of the casing 2. 35 The projecting end of this rod provides a handle or finger-piece by means of which the fulcrum block may be shifted from the exterior of the casing whenever it is desired to 40 vary the power action of the lever.

Communicating with the outer end of the chamber 2 at its top is a cylinder 32 in which operates a piston 33, and communicating with the outer end of the chamber 2 at its bottom 45 is a diaphragm chamber 34 containing a weighted diaphragm 35. Rods 36 and 37 respectively connect the piston 33 and the diaphragm 35 with the outer end of the lever 26, said rods being connected with the lever 50 by means of a pin, bolt or other suitable fastening 38. The piston 33, diaphragm 35, lever 26 and spring 25 provide a system of controlling mechanism governing the operation of the valves 14-15, the spring 25 operating to hold the valve seated or closed against 55 any predetermined pressure, while the piston 23 acts as a power agent to force the valve open against the resistance of the spring when such predetermined pressure is exceeded, and the diaphragm 35 operates upon 60 the opening of the valve as a retarding device to prevent closing of the valve by the spring and to hold it open until the pressure has fallen to a predetermined degree.

65 Figure 1 shows diagrammatically and in

section the application of the valve for use as an automatic stop cock in a pipe line leading from a well for the flow of the gas and oil therefrom, such pipe line including pipe sections 39 and 40 between which the valve is disposed, the pipe 39 constituting a high pressure pipe leading from the well and communicating with the inlet port 8, and the pipe 40 constituting a low pressure pipe communicating with the outlet port 9 and leading in 70 practice to any suitable point at which the released gas and oil is to be delivered. It will be observed that the lower side of the piston and upper side of the diaphragm 35 are in constant communication with valve 75 chamber 4 and are therefore, when the valve 14-15 is closed, in communication with the low pressure pipe 40 and subjected to the force of whatever pressure there may be 80 therein. When the valve 14-15 is opened 85 for a pressure relieving action, communication is established between the high and low pressure pipe, both chambers of the valve and the casing 2, so that the lower side of the piston 32 and upper side of the diaphragm 35 90 are subjected to the pressure in both sides of the pipe line, whatever it may be. A by-pass pipe 41 is provided for connecting the outer end of the cylinder 32 with the passage 7 or some other suitable part of the gas conduit 95 at the high pressure side of the valve, so that the upper face of the piston 33 will be constantly exposed to the pressure in the pipe 39 whatever it may be.

In practice it may be assumed that the 100 spring 25 has a valve closing pressure sufficient to hold the valve 14-15 closed, against the high pressure from pipe 39 acting on the outer face of the piston 33, until a predetermined high pressure, say a pressure of 100 105 lbs., is reached in the high pressure pipe 39 between the valve and the well to be controlled. The gas and oil flowing from the well may therefore continue to flow between the well and the control valve until the pressure in the pipe 39 is built up to the predetermined high pressure, that is, 100 lbs. At 110 this pressure the piston 33 is forced down in the cylinder 32 and transmits its power to the lever 26 to open the valves 14-15 115 against the resistance of spring 25, such valve opening action of the piston 33 being supplemented, as soon as the valve is opened to any extent, by the force of the released high pressure filling the valve casing and lever casing and all parts of the system and whereby the diaphragm 35 is depressed in its casing 34 and exerts a downward pull on the outer 120 end of the lever 26. The valve 14-15 will thus be opened for the flow of gas from pipe 39 into pipe 40 and will be held open against the pressure of the spring 25, which now preponderates in force over the piston 33, by the action of the diaphragm 35, such diaphragm acting as a retarder under the pres- 125 130

sure in the system and coacting with the piston 33 to hold the valve open against the action of the closing spring until the pressure in the pipe line has fallen to the predetermined low degree. The powers of these forces, namely, the spring, the piston and the diaphragm, controlling the action of the valve with or in the absence of any material amount of fluid pressure, are so correlated, or 10 adjusted with relation to each other, that the retarder maintains control as against a final valve closing action until the pressure in the pipe line has fallen to a very low degree, or is negligible so far as its working 15 pressure on the valve elements is concerned, whereupon the valve will close under the action of the spring in a positive, certain and reliable manner and cut off communication between the pipes 39 and 40. Pressure will 20 then be allowed to again build up in the pipe 39 until the minimum predetermined pressure therein is reached, whereupon the valve will again be operated to allow the pressure to discharge. It will thus be seen that by 25 the action of this valve the pressure of the gas flowing from the well may be allowed to build up to any point suitable to effect the flow of oil from the well at predetermined periods, and then released and allowed to 30 again build up, so that a positive building up action at more or less regular periods will be automatically effected and governed for the periodic raising of the oil from the well. It will, of course, be understood that by adjustment of the spring and the shifting fulcrum 35 the applied powers of the valve mechanism controlling the valve and acting with or in opposition to the flow of pressure forces may be governed and controlled to adapt the valve 40 to operate very successfully and at wide variations of pressures within given limits.

If desired a suitable drain pipe connection 42 may be provided between the upper portion of diaphragm chamber 34 above the 45 diaphragm and the valve chamber 4 to permit any liquids finding their way through the chamber 2 into the diaphragm chamber to discharge back into the pipe system, thus preventing interference of any such deposits with 50 the operation of the diaphragm.

Having thus fully described my invention, I claim:—

1. In an automatic stop cock or valve for fluid pressure pipe lines, a valve casing having an inlet and an outlet for connection, respectively, with high and low pressure sides 55 of a pipe line, an automatically closing valve in said casing controlling said inlet and outlet, fluid pressure controlled means for opening the valve when a predetermined high pressure in the high pressure side of the line is reached, and fluid pressure controlled means for retarding the closing of the valve until a predetermined low pressure in the 60 high pressure side of the line is reached.

2. In an automatic stop cock or valve for fluid pressure pipe lines, a valve casing having an inlet and an outlet for connection, respectively, with the high and low pressure sides of a pipe line, a valve in said casing controlling said inlet and outlet, a spring for closing the valve and holding the valve closed until a predetermined high pressure is reached in the high pressure side of the pipe line, a fluid pressure actuated member exposed to 70 the pressure in the high pressure side of the line and operative to open the valve against the resistance of the spring when the predetermined high pressure is reached, and a fluid pressure controlled device for retarding the 75 closing of the valve under the action of the spring as the pressure falls until a predetermined low pressure is reached.

3. In an automatic stop cock or valve for fluid pressure pipe lines, a valve casing having an inlet and an outlet for connection, respectively, with the high and low pressure sides of a pipe line, a valve in said casing controlling said inlet and outlet, a spring for closing the valve and holding the valve 80 closed until a predetermined high pressure is reached in the high pressure side of the pipe line, a fluid pressure actuated member exposed to the pressure in the high pressure side of the line and operative to open the valve 85 against the resistance of the spring when the predetermined high pressure is reached, and a diaphragm subjected when the valve is opened to the pressure in the line and acting under such pressure for retarding the closing of the valve under the action of the spring as the pressure falls until a predetermined low pressure is reached.

4. In an automatic stop cock or valve for fluid pressure pipe lines, a valve casing having an inlet and an outlet for connection, respectively, with the high and low pressure sides of a pipe line, a valve in said casing controlling said inlet and outlet, means for closing the valve and holding the valve closed 90 until a predetermined high pressure is reached in the high pressure side of the pipe line, a piston exposed to the pressure in the high pressure side of the line and operative to open the valve against the resistance of the 95 spring when the predetermined high pressure is reached, and a fluid pressure controlled device for retarding the closing of the valve under the action of the spring as the pressure falls until a predetermined low pressure is reached.

5. In an automatic stop cock or valve for fluid pressure pipe lines, a valve casing having an inlet and an outlet for connection, respectively, with the high and low pressure 105 sides of a pipe line, a valve in said casing controlling said inlet and outlet, means for closing the valve and holding the valve closed 110 until a predetermined high pressure is reached in the high pressure side of the line, a piston exposed to the pressure in the high pressure side of the line and operative to open the valve against the resistance of the 115 spring when the predetermined high pressure is reached, and a fluid pressure controlled device for retarding the closing of the valve under the action of the spring as the pressure falls until a predetermined low pressure is 120 reached.

a fluid pressure actuated member exposed to the pressure in the high pressure side of the line and operative to open the valve against the action of the valve closing means when the predetermined pressure is reached, and a diaphragm subjected when the valve is opened to the pressure in the line for retarding the closing of the valve until a predetermined low pressure is reached.

10. In an automatic stop cock or valve for fluid pressure pipe lines, a valve casing having an inlet and an outlet for connection, respectively, with the high and low pressure sides of a pipe line, an automatically closing valve for closing communication between the high and low pressure sides of the pipe line until a predetermined high pressure in the high pressure side is reached, a fluid pressure actuated piston for opening the valve when the predetermined high pressure is reached, and a fluid pressure actuated retarder diaphragm for holding the valve open until the line pressure has fallen to a predetermined low pressure.

25. In an automatic stop cock or valve for fluid pressure pipe lines, a valve casing having an inlet and an outlet for connection, respectively, with the high and low pressure sides of a pipe line, an automatically closing valve for closing communication between the high and low pressure sides of the pipe line until a predetermined high pressure in the high pressure side is reached, a lever fulcrumed intermediate of its ends and coupled 30 at one of its ends to the valve, a fluid pressure actuated device acting on the other end of the lever for opening the valve when the predetermined high pressure is reached, a fluid pressure controlled retarder acting also 35 on the second-named end of the lever to hold the valve open after an opening movement until a predetermined low pressure in the pipe line is reached, and means for varying the fulcrum point of the lever.

40. In an automatic stop cock or valve for fluid pressure pipe lines, a valve casing having an inlet and an outlet for connection, respectively, with the high and low pressure sides of a pipe line, a valve in said casing 45 controlling said inlet and outlet, a spring for closing the valve and holding the valve closed until a predetermined high pressure is reached in the high pressure side of the pipe line, means including a piston exposed 50 to the pressure in the high pressure side of the pipe line for closing the valve when the predetermined high pressure is reached, and a fluid pressure controlled diaphragm acting on said means after the valve is opened for 55 holding the valve open until the pressure falls to a predetermined low pressure.

35. In an automatic stop cock or valve for fluid pressure pipe lines, a valve casing having an inlet and an outlet for connection, respectively, with high and low pressure sides

of a pipe line, an automatically closing valve in said casing for closing communication between the inlet and outlet until a predetermined high pressure in the high pressure side of the pipe line is reached, a lever connected with said valve, a fluid pressure actuated element coupled to said lever and operated by fluid pressure on the high pressure side for opening the valve when the predetermined high pressure is reached, and a retarder coupled to the lever for retarding the closing action of the valve after a valve opening movement until the pressure has fallen to a predetermined low degree.

10. In an automatic stop cock or valve for fluid pressure pipe lines, a valve casing having an inlet and an outlet for connection, respectively, with high and low pressure sides of a pipe line, a valve in said casing and controlling said inlet and outlet, a spring acting on the valve for normally holding it closed until a predetermined high pressure in the high pressure side is reached, a lever coupled to the valve, a fluid pressure element exposed to the pressure in the high pressure side and acting in opposition to the spring to open the valve when a predetermined high pressure is reached, and a fluid pressure controlled element coupled to the lever and acting after the opening of the valve to retard its closing movement and hold it from closing until a predetermined reduction of pressure in the pipe line has occurred.

11. In an automatic stop cock or valve for fluid pressure pipe lines, a valve casing having an inlet and an outlet for connection, respectively, with high and low pressure sides of a pipe line, a valve in said casing and controlling said inlet and outlet, said valve being adapted to automatically close under a predetermined low pressure in the pipe line and to hold the valve closed until a predetermined high pressure is reached in the high pressure side of the pipe line, a piston operatively connected with the valve and exposed to the pressure in the high pressure side of the pipe line for opening the valve when the predetermined high pressure is reached, and a fluid pressure controlled retarder coupled to the valve and exposed to the line pressure when the valve is opened to oppose a diminishing resistance to the closing of the valve as the pressure falls and adapted to permit the valve to close when the predetermined low pressure is reached.

12. In an automatic stop cock or valve for fluid pressure pipe lines, a valve casing having an inlet and an outlet for connection, respectively, with high and low pressure sides of a pipe line, a valve in said casing and controlling said inlet and outlet, a spring acting on the valve for closing the valve at a predetermined low pressure and holding it closed until a predetermined high pressure in the high pressure side of the pipe line

is reached, a lever coupled to the valve, a piston subjected to the force of the fluid pressure in the high pressure side of the line and coupled to the lever for transmitting motion to the valve to open the same when the predetermined high pressure is reached, and a diaphragm coupled to the lever and exposed to line pressure when the valve is opened for opposing a retarding resistance to the closing of the valve under the pressure of the spring until the pressure is reduced to the predetermined low degree in the pipe line.

In testimony whereof I affix my signature.
